UNITED STATES PATENT OFFICE

95,872

DESIGN FOR A DECANTER OR SIMILAR ARTICLE

Eugene Stahl, Moundsville, W. Va., assignor to Fostoria Glass Company, Moundsville, W. Va.,
a corporation of West Virginia

Application April 13, 1935, Serial No. 56,362

Term of patent 7 years

To all whom it may concern:

Be it known that I, Eugene Stahl, a citizen of the United States of America, and resident of Moundsville, county of Marshall, and State of West Virginia, have invented a new, original, and ornamental Design for a Decanter or Similar Article, of which the following is a specification, reference being had to the accompanying drawing, in which—

Figure 2 is a side elevation of the same illustrating the design of the remaining three sides thereof; and—

I claim—

The ornamental design for a decanter or similar article, substantially as shown and described.

EUGENE STAHL.
